UNITED STATES PATENT OFFICE.

ASBJORN SONSTHAGEN, OF LONDON, ENGLAND.

CHOCOLATE AND LIKE DEPOSITING AND COATING MACHINE.

Application filed April 11, 1922. Serial No. 551,533.

To all whom it may concern:

Be it known that I, ASBJORN SONSTHAGEN, a subject of the King of Norway, residing in London, England, have invented 5 certain new and useful Improvements in Chocolate and like Depositing and Coating Machines, of which the following is a specification.

This invention relates to chocolate and 10 like depositing and coating machines in which the material is discharged from a hopper through nozzles or apertures. With machines of this type considerable variation 15 in the rate of discharge of the material is necessary owing to variations in the degree of viscosity of said liquid, and/or the size of the aperture or apertures in the discharge opening or nozzles as the case may be, so that the discharge may either be too slow, 20 in which case the cores are not coated to the desired thickness, or too brisk in which case the material will spurt out from the discharge nozzle or opening causing considerable waste, the material further being scattered over the machine.

The present invention has for its object 25 certain improvements in machines of the type specified whereby the discharge may be regulated and take place at the desired rate.

According to this invention a pump or 30 other means of creating pressure is employed whereby the liquid may be forced through the nozzle or discharge opening, said pump or other device being driven at 35 or operating at a constant speed. In order that the rate of discharge may be varied a by-pass is provided or other provision is made whereby when so desired a certain portion of the liquid passing under pressure 40 to the discharge is diverted therefrom whereby the pressure at said discharge may be readily regulated.

The present invention may be applied to 45 machines having a fixed hopper or to machines in which a swinging hopper is employed such for example as that described and illustrated in the specification and drawings of my Letters Patent No. 1,458,368.

In order that the invention may be the 50 better understood drawings are appended in which:—

Fig. 1 is a front elevation of a machine 55 of known type embodying the present invention,

Fig. 2 is a plan of the upper end of the machine.

Fig. 3 is a side elevation,

Fig. 4 is a sectional view to a larger scale 60 showing certain details,

Fig. 5 is a similar view showing more 65 clearly the by-pass by which the material is returned to the hopper in order to relieve the pressure at the discharge nozzles,

Fig. 6 is a part sectional view showing 70 part of the driving mechanism for the pump.

Fig. 7 is a plan showing more clearly the 75 means for imparting movement to the hopper.

Referring to the accompanying drawings 80 1 indicates a pedestal supporting a member 2 preferably in a manner such as to permit of the vertical adjustment of said member 2.

Secured to the upper end of the part 2 is 85 an arm in the form of a circular rod or bar 3 and from which arm there is suspended by rods 5 in a manner such as to permit its movement horizontally in all directions a hopper. The hopper is formed in two parts of which the upper 6 is supported by the rods 5 whilst the other part 7 is bolted or otherwise secured to the lower end of part 6, and is provided with a nozzle bar 6^a

90 having nozzles such as 8 through which, as will be hereafter more fully explained, the material is forced and falls on to the bodies to be coated or decorated and for which bodies a suitable support, not shown, is provided. The nozzle bar is so constructed as to 95 be capable of ready removal and replacement, bolts 6^b being provided for this purpose, said nozzle bar forming, in conjunction with the rollers 9, 10, hereinafter referred to, a pressure chamber. As will be seen on reference to Fig. 5 the part 7 is so shaped adjacent the nozzles as to form chambers in

100 which are placed rollers 9, 10 provided with radial projections 11 after the manner of the teeth of a gear wheel said projections at their ends fitting snugly against the curved surfaces of the part 6^a and 7.

The projections of the respective rollers 9, 10 are arranged as shown to intermesh and the rollers are divided into a number of sections, spaces 10^a being left between the sections and with which spaces engage

105 plates or partitions 10^b located between the openings 12 through which the material passes to the nozzles 8, said plates being se- 110

cured to the nozzle bar by saw cuts or otherwise.

As the rollers 9, 10 rotate the material is forced through the nozzles the rate of flow being proportionate to the speed of said rollers. It may be found that under some circumstances the rate of discharge is too rapid and in order that this difficulty may be met there is provided a passage 13 leading from the discharge openings back to the hopper. In order to regulate the passage of the material back to the hopper a valve 14, operable by handle 14^a, is provided. It is thus possible to cause the material to return to the hopper and the amount passing through the nozzles may thus be adjusted with considerable nicety.

In Fig. 5 two rollers are shown but under some circumstances it may be found sufficient to employ only one such roller.

In order that the material within the hopper may be retained at the desired consistency the hopper is provided with a jacket 15 through which hot water is caused to circulate by means of a pump 16 mounted upon the pedestal 1, the pedestal containing a heater 17 heated by steam supplied through the pipe 18 and controlled by the cock 19. 20 indicates the return pipe. The hot water is supplied to the jacket 15 through the flexible pipe 21.

Secured to the spindle of the roller 9, as shown in Fig. 4, is a shaft 23. 23^a indicates a clutch whereby the shaft 23 may be clutched to a shaft 22, said clutch being operated by a rod 23^b provided with a handle 23^c, Fig. 1, whereby not only may clutch 23^a be operated but the hopper may be swung by the same hand horizontally in all directions.

40 The rod 23^b at its inner end is provided with a cam surface engaging a similar surface upon a pin or stud carrying a fork 23^d which straddles a bobbin 23^e, Fig. 4. A spring opposes the movement of the bobbin in one direction. By turning the rod 23^b in one direction the engaging cam surfaces act to move the fork and the pump is de-clutched.

50 Rotary movement of the rod in the other direction will permit the spring to clutch the pump to the spindle of pinion 24.

The shaft 22 carries a bevel wheel 24^a in gear with a second bevel wheel 25 having a shaft 25^a secured in a sleeve 26 having at its upper end a bore of square cross-sectional outline and with which engages a square extension 27 upon the end of a vertically disposed shaft 28, the arrangement being such as to permit of universal movement of the hopper without jamming the end of the shaft 28.

60 The upper end of the shaft 28 is provided with an extension 29 similar to that 27 just referred to and contained within a sleeve 29^a shown in Fig. 6. Also engaging the

sleeve 29^a is a short shaft 30 provided with a bevel wheel 31 engaging a second wheel 32 freely mounted upon the aforesaid rod or bar 3. Preferably the sleeve 29^a is of sufficient length to permit the shaft 28 to be 70 lifted a sufficient distance to clear the sleeve 26 when the shaft 28 may be removed.

Also freely mounted upon the rod 3 is a worm wheel 33, Figs. 1 and 6, said worm wheel being driven through gearing to be 75 presently more fully described.

Provision is made whereby the bevel wheel 32 is frictionally driven by the worm wheel 33, the friction contact between the parts being adjusted by means of the lever 34 pivotally mounted at 35 and which lever at one end engages a bobbin 36 between which and the inner face of worm wheel 33 is inserted a helical spring 37, a ball or like bearing 38 being inserted between the end of the spring and the face of the said worm wheel 33. 39 indicates a screw having a milled head and supported by a projection 40 upon a bracket 41 carrying the sleeve 29^a. The screw 39 engages the free end of the lever 34, said screw serving to regulate the compression of spring 37 and consequently the extent of the frictional contact between worm wheel 33 and the bevel wheel 32. By this means it is possible to so arrange the friction between the parts, that should the material in the hopper solidify or otherwise attain such a degree of viscosity as would otherwise cause the projections of rollers 9, 10 to become damaged the parts will slip and permit the rollers to remain stationary. Preferably a casing is provided for the adjusting screw 39 whereby same may be protected from operation by persons other than those competent to effect the desired adjustments.

The motion for the various parts is secured by means of variable speed gear comprising a shaft 42 mounted on a swing bracket 43, said shaft being provided with fast and loose pulleys 44, 45. The bracket 43 is pivotally mounted upon the arm 46 forming part of a plate 47 mounted upon the upper end of the part 2 of the pedestal 1. The plate 47 carries brackets 48 in which is mounted a shaft 49 and mounted upon the shaft just referred to and shaft 42 are oppositely coned pulleys 50, 51 around which passes a belt 52 shown in Fig. 3. The belt is adjustable lengthwise of the pulleys 50, 51 by the fork 53 carried by the screw 54 operable by the hand wheel 55.

In order that the belt 52 may be tensioned, when so desired, a swivel nut 56 is provided upon an extension 57 of the swing bracket 43, a screw 58 passing through said nut and engaging the under-side of the head 58^a carrying plate 47. Secured to the shaft 49 is a bevel wheel 59 engaging a bevel wheel 59^a upon a shaft 60, said shaft 60 carrying

a worm 60^a engaging the afore-mentioned worm wheel 33. Secured to the shaft 42 is a pulley 61 around which passes a belt 52 by which motion is transmitted to a second pulley 63 mounted upon a shaft *x*, Fig. 3, carried by a bracket 64 and provided with a bevel wheel 63^a engaging a second bevel wheel 65 mounted upon a shaft carried by the brackets 66, 66^a and provided at its upper end with a disc 67 slotted to receive a head 67^a upon a stud 68 upon which is pivotally mounted an arm 69 pivotally connected to the hopper. The arm 69 is slotted to permit the passage of the stud 68, said stud moving longitudinally of said arm during the rotation of the disc 67. 70 indicates a pinion upon the spindle of disc 67 engaging a pinion 68^a upon a second disc 71 such as that 67 just before referred to and to which disc there is secured a stud 72 engaging the outer end of the arm 69. By this means an eccentric motion is imparted to the hopper in order to produce decorative patterns upon the goods.

25 The parts may, however, be readily disconnected to enable the hopper to be moved by hand by removing the studs 68 and 72 to free arm 69 which may then be disconnected from the hopper.

30 73 indicates a pulley secured to the spindle carrying pulley 63 and by which pulley motion is transmitted through belt 73^a to a pulley 74 upon the pump 16.

35 75 indicates a brake whereby the speed of the shaft carrying pulleys 63 and 73 may be controlled by hand from the table carrying the goods, for which purpose a chain or other flexible body 76 is provided led around a guide pulley 77 to the desired point.

40 Claims:

1. A machine for coating or decorating sweetmeats, comprising a hopper movable horizontally in all directions, nozzles for the passage of the material from the hopper, pressure producing means for the material in the hopper said means being located in said hopper, a handle for manipulating the hopper, said handle also controlling the action of the pressure producing means.

50 2. A machine for coating or decorating sweetmeats, comprising a hopper moving horizontally in all directions, nozzles for the passage of the material from the hopper, a by-pass for the material from the nozzles to the hopper, a valve controlling the passage of the material to the hopper, a handle for controlling said valve, pressure producing means for the material in the hopper, said means being located in said hopper, a handle for manipulating the hopper said handle controlling the action of the pressure producing means.

60 3. A machine for coating or decorating sweetmeats, comprising a hopper moving horizontally in all directions, nozzles for the

passage of the material from the hopper, a by-pass for the material from the nozzles to the hopper, a valve controlling the passage of the material to the hopper, a handle for controlling said valve, pressure producing means for the material in the hopper said means being located in said hopper, a friction drive for said pressure producing means, means for adjusting the pressure between the friction surface of said drive, a handle for manipulating the hopper said handle controlling the action of the pressure producing means.

4. A machine for coating or decorating sweetmeats, comprising a hopper moving horizontally in all directions, nozzles for the passage of the material from the hopper, a by-pass for the material from the nozzles to the hopper, a valve controlling the passage of the material to the hopper, a handle for controlling said valve, pressure producing means for the material in the hopper said means being located in said hopper, a friction drive for said pressure producing means, means for adjusting the pressure between the friction surfaces of said drive, a main drive, means for transmitting motion from said main drive to said friction drive comprising a vertically disposed shaft capable of universal movement at both ends, a handle for manipulating the hopper said handle controlling the action of the pressure producing means.

5. A machine for coating or decorating sweetmeats, comprising a hopper movable horizontally in all directions, nozzles for the passage of the material from the hopper, pressure producing means for the material in the hopper said means being located in said hopper and comprising rollers having radially disposed vanes, divisions upon said rollers, fixed partitions engaging said divisions to form compartments each communicating with the discharge nozzles, a handle for manipulating the hopper, said handle controlling the action of the pressure producing means.

6. A machine for coating or decorating sweetmeats, comprising a hopper movable horizontally in all directions, nozzles for the passage of the material from the hopper, pressure producing means for the material in the hopper said means being located in said hopper, a nozzle bar separate from the hopper, bolts removably securing said nozzle bar to said hopper, a handle for manipulating said hopper, said handle controlling the action of the pressure producing means.

7. A machine for coating or decorating sweetmeats, comprising a hopper movable horizontally in all directions, pressure producing means for the material located in said hopper, having radially disposed vanes, divisions upon said rollers, fixed partitions engaging said divisions to form compartments

ments each communicating with the discharge nozzles, a by-pass from the nozzles to the hopper, a valve controlling said by-pass, a handle for controlling said valve, a main drive, a frictional drive having means for regulating the pressure between the friction surfaces of said drive, a shaft for transmitting motion from the main to the frictional drive said shaft being capable of universal movement at each end, a nozzle bar separate

from the hopper, bolts removably securing said nozzle bar to said hopper, a handle on the hopper, a connection between said handle and one of the members of the friction drive whereby said handle serves both to manipulate the hopper and to control the action of the pressure producing means. ¹⁵

In testimony whereof I have hereunto set my hand.

ASBJORN SONSTHAGEN.
